UNITED STATES PATENT OFFICE.

JOHANNES F. HARTZ, OF DETROIT, MICHIGAN.

DESIGN FOR A DEPURATOR.

SPECIFICATION forming part of Design No. 22,510, dated June 6, 1893.

Application filed December 6, 1892. Serial No. 454,285. Term of patent 7 years.

To all whom it may concern:

Be it known that I, JOHANNES F. HARTZ, a citizen of the United States, residing at Detroit, county of Wayne, and State of Michigan, have invented and produced a new and original Design for a Vaginal-Depurator, of which the following is a specification, reference being had to the accompanying drawings, forming a part thereof.

10 The design is illustrated in the accompanying drawings wherein—

Figure 1 is a side elevation. Fig. 2 is a top plan view, and Fig. 3 is a front elevation showing the outer or edge contour of the disk.

15 In the drawings B represents the nipple to which the rubber tube is attached, B' the dis-

charge nipple, and C the nozzle. This design consists in the peculiar shape of the outer or rear face of the disk A, which face is convexed from the base of the nipples to the edge 20 at all points, the arc of the curve above the nipples being less than that of the portion below as shown in Fig. 1. The curvatures at the sides of the nipples are of substantially the same arc, as shown in Fig. 2. 25

What I claim as new is—

The design for a depurator as herein shown and described.

JOHANNES F. HARTZ.
